TRIMMING DEVICE

Elmer G. Nielsen, Chicago, Ill.

Application February 25, 1935, Serial No. 8,142

3 Claims. (Cl. 164—44)

My invention relates to trimming devices, and has among its objects and advantages the provision of an improved shingle cutter.

An object of the invention is to provide a novel table designed for connection with a conventional shingle cutter and in which means is embodied whereby the shingle may be easily and effectively cut for size and angularity.

A further object is to provide a novel mounting for the table, whereby the necessity for reconstructing any part of the original shingle cutter is eliminated.

In the accompanying drawing:

Fig. 1 is a top plan view of a shingle cutter partly in section illustrating my invention applied thereto;

Fig. 2 is a side elevation partly in section;

Fig. 3 is a sectional view along the line 3—3 of Fig. 1;

Fig. 4 is a sectional view along the line 4—4 of Fig. 3; and

Fig. 5 is a sectional view along the line 5—5 of Fig. 1.

In the embodiment selected to illustrate my invention, I make use of a conventional shingle cutter 10 comprising a beam 12 cast integrally with supporting legs 14. This beam includes a bottom reinforcing flange 16 and an upper enlarged part 18 carrying a cutting blade 20. A movable blade holder 22 is pivotally connected at 24 with an enlarged part 26 of the beam 12. The movable blade holder 22 includes an enlarged part 28 (see Fig. 5) which supports a companion cutting blade 30 lying in the same plane as the blade 20.

The opposite end of the blade holder 22 has an integral ear 32 pivotally connected at 34 with an operating handle 36. The latter is pivotally connected at 38 with the beam 12 at 40 through the medium of a link 42. Thus, raising and lowering of the free end of the handle 36 moves the cutting blade 30 toward and away from the blade 20. A lug 44 carried by the blade holder 22 is positioned in the path of a similar lug 46 carried by the handle 36. Engagement between the two lugs when the handle is positioned according to Fig. 2 prevents the load of the blade holder 22 and its associated structure from resting directly upon the blade 20. However, the relation is such that building material in the nature of asbestos shingles and equivalent covering material is effectively severed by the blades 20 and 30. All the structure above described is old in the art.

My invention includes a metallic table 48 hav-

ing its ends connected with the horizontal reaches 50 and 52 of two brackets 54 and 56, respectively. The connection between the table 48 and the reaches 50 and 52 may comprise rivets 58 having countersunk heads 60. Referring to Fig. 1, the beam 12 is provided with two laterally extending parts 62 each having a small circular face 64 comprising supporting means for the shingle to be cut in the original cutter. I provide two openings 66 in the table 48 for accommodating the faces 64 which terminate flush with the upper face of the table.

Each of the brackets 54 and 56 is U-shaped in configuration (see Figs. 3 and 5) so that the brackets substantially encircle the beam 12. Each bracket including the horizontal reaches 50 and 52 is substantially L-shaped in cross section so as to strengthen the parts. The legs 68 and 70 of both brackets 54 and 56 are spaced apart sufficiently far to freely receive the beam 12 to permit quick and easy placement. Each of the legs 68 is depressed at 72 to provide additional space for the flange 16 of the beam 12.

The legs 68 lie against one side of the enlargement 18 and I provide a filler block 74 between the legs and the beam proper. Each leg 70 carries a screw 76 positioned to engage the beam 12 for fastening the bracket to the beam. I prefer to extend the edge 78 of the table beyond the legs 68 so that it rests upon the enlarged part 18 in close relation with the cutting blade 20. The opposite edge of the table is bent down at 80 and both ends are similarly bent as indicated at 82.

Upon the table 48 I mount a ruled guide bar 84. This bar comprises a standard wood rule 86 mounted upon a metal bar 88. I recess the rule 86 at 90 for the reception of a protractor 92. A rivet 94 fastens one end of the ruler 86 to the bar 88, while the opposite ends of the two parts are connected together by a bolt 96 which provides a pivot for the guide bar 84. The bolt extends through aligned openings in both parts of the guide bar and the protractor and the table 48 and its horizontal supporting reach 54, (see Fig. 5).

The protractor 92 is additionally fastened to the guide bar 84 by a rivet 98 which passes through the metal bar 88 (see Fig. 4). I provide a curved slot 100 in the protractor for the reception of a bolt 102 extending through a cross bar 104 riveted to the table 48 at 106 (see Fig. 5). The cross bar 104 is arranged at right angles to the blades 20 and 30.

The bolt 102 is squared at 108 and extends

through aligned openings in the table 48 and the reach 50 of the bracket 54. I mount a sleeve 110 upon the bolt and provide the latter with a grip part 112 having threaded relation with the bolt 5 so that the protractor 92 may be secured in various adjusted positions for supporting the guide bar 84 at the desired angle with respect to the cutting blades of the device.

In operation, the guide bar 84 may be shifted to 10 a position at right angles to the cutting blades 20 and 30, in which case it provides an abutment for supporting the shingles so that the edge may be cut at right angles to the edge abutting the guide bar 84. With the guide bar in the latter 15 position, it is prevented from swinging further because of its engagement with the cross bar 104. As a guide to cutting shingles a predetermined width, I provide guide lines 114 in the 20 surface of the table 48. These lines may be spaced one inch apart or at shorter intervals. In cases where it is desired to make an angular cut, the 25 guide bar 84 is adjusted to align a division on the protractor representing the required angle with the edge 116. With the grip part 112 turned down tightly, the guide bar 84 will be firmly supported at the necessary angle.

My invention provides a convenient table and 30 guide means co-operating therewith for facilitating the cutting of shingles. The construction 35 is designed so that it may be easily and quickly connected with equipment of standard design.

Without further elaboration, the foregoing will 35 so fully explain my invention that others may, by applying current knowledge, readily adapt the same for use under various conditions of service.

I claim:

1. The combination with a shingle cutter com-

prising a stationary support in the nature of a narrow beam having a blade and a movable support connected with the former and having a blade arranged in operative relation with the first blade, of a pair of generally U-shaped brackets having 5 horizontally aligned arms, the U-shaped parts of said brackets substantially encircling the stationary support, adjustable means for connecting the U-shaped parts with the stationary support, and a table carried by said horizontally aligned 10 arms.

2. In a shingle cutter having a normally vertically positioned beam provided with a cutting blade fastened to its upper edge, a supporting table projecting laterally from the beam and having an 15 edge extending over the upper edge of said beam, a bracket for supporting the table, said bracket comprising a horizontal reach connected with the table for supporting the same and a U-shaped 20 part, said beam being positioned within said U-shaped part, and means for detachably securing the U-shaped part of the bracket to the beam.

3. In a shingle cutter, a flat support normally positioned in a vertical plane and having a flat 25 upper edge, a knife narrower than the upper edge and connected therewith, a table, brackets fixedly secured to the table and having U-shaped parts for receiving said support, one leg of each U-shaped part bearing against one side of said support, said table extending inwardly of the 30 U-shaped parts and arranged to extend over a portion of said upper edge, and means carried by the other legs of said U-shaped parts and co-operating with said support for fixedly connecting the parts therewith.

ELMER G. NIELSEN.
